(57) **CLAIM**

The ornamental design for a blower cart with handle, as shown and described.

DESCRIPTION

FIG. 1 is a top, side and front isometric view of a blower cart with handle showing my new design.

FIG. 2 is a left side thereof; the right side view being a mirror image of the left side.

FIG. 3 is a front view thereof.

FIG. 4 is a back thereof.

FIG. 5 is a top thereof; and,

FIG. 6 is a bottom thereof.

The broken lines in the figures are for the purpose of illustrating portions of the blower cart with handle which form no part of the claimed design.
